UNITED STATES PATENT OFFICE

124,904

DESIGN FOR A NURSING BOTTLE HOLDER

Robert W. Palmer and Harold K. Nehls,
Buffalo, N. Y.

Application November 12, 1940, Serial No. 96,467

Term of patent 7 years

To all whom it may concern:

Be it known that we, Robert W. Palmer and Harold K. Nehls, citizens of the United States, residing at Buffalo, in the county of Erie and State of New York, have invented a new, original, and ornamental Design for a Nursing Bottle Holder, of which the following is a specification, reference being had to the accompanying drawing, forming part thereof.

In this drawing:

The figure is a perspective view of a nursing bottle holder embodying our new design.

We claim:

The ornamental design for a nursing bottle holder, as shown.

ROBERT W. PALMER.
HAROLD K. NEHLS.
